UNITED STATES PATENT OFFICE.

ALBERT B. SCHOFIELD, OF BROOKLYN, NEW YORK.

DESIGN FOR A BOX-OPENER.

SPECIFICATION forming part of Design No. 24,585, dated August 20, 1895.

Application filed July 5, 1895. Serial No. 555,065. Term of patent 14 years.

To all whom it may concern:

Be it known that I, ALBERT B. SCHOFIELD, of Brooklyn, in the county of Kings and State of New York, have invented and produced a new and original Design for Box-Openers, of which the following is a specification.

The leading features of my design consist in a box-opener having a flattened blade, gradually increasing in width and decreasing in thickness from a rounded shank, the shank itself having its free end turned at an angle to the blade, as shown.

In the accompanying drawing the blade,

which gradually increases in width and decreases in thickness from a rounded portion 15 of the shank, is denoted by A, the rounded portion of the shank by B, and the free end of the rounded shank, which is turned at an angle to the plate, by C.

What I claim is—

The design for a box opener, as herein shown and described.

ALBERT B. SCHOFIELD.
